UNITED STATES PATENT OFFICE.

EDWARD M. HEWLETT, OF SCHENECTADY, NEW YORK, ASSIGNOR TO GENERAL ELECTRIC COMPANY, A CORPORATION OF NEW YORK.

CIRCUIT-CONTROLLING CONTACT.

1,074,431.

Specification of Letters Patent. Patented Sept. 30, 1913.

Application filed October 29, 1910. Serial No. 589,689.

To all whom it may concern:

Be it known that I, EDWARD M. HEWLETT, a citizen of the United States, residing at Schenectady, county of Schenectady, State 5 of New York, have invented certain new and useful Improvements in Circuit-Controlling Contacts, of which the following is a specification.

My invention relates to contacts for controlling electric circuits and more particularly to shunt contacts such as are used on circuit breakers and similar devices to take the arc which is formed as the circuit is broken.

15 It is desirable that the contacts of a circuit controlling device, particularly the shunt contacts of a circuit breaker, should make good electrical engagement with each other when the circuit controlling device is 20 in the closed position, and that the contacts separate in a definite manner so that the arc formed when the circuit is finally broken will occur at some definite and predetermined point on the contacts where the damage done by the arc will be a minimum.

The object of my invention is to provide coöperating contacts, particularly adapted for use as shunt contacts in a circuit breaker, but also useful in other devices, in which 30 there is a simple and rugged mounting of such a character that as the contacts are brought together they make good electrical contact, in which the movement of the contacts relatively to each other is positively controlled in such a manner that as the circuit is opened the contacts separate in a definite and predetermined manner, the shunt contacts for circuit breakers being preferably arranged to swing away from each other at 35 the bottom to such an extent that the final break in the circuit takes place near the upper edge of the contacts; in which the contacts are yieldingly held in proper relation by a single spring or similar device 40 mounted so as to be fully protected by the contacts from accident or injury; and which may be applied to any of the well-known and standard forms of circuit breakers and circuit controlling devices without requiring 45 extensive alterations and changes in them. When my invention is embodied in shunt contacts of which the engaging surfaces are partly metal and partly carbon the contacts

have such a movement relatively to each other that as the circuit breaker opens 55 the metallic surfaces of the shunt contacts swing away from each other while the carbon surfaces are still in firm engagement, so that arcing takes place on the carbon surfaces.

60 My invention will best be understood in connection with the accompanying drawings in which, merely for the purpose of illustrating one of the various forms in which my invention may be embodied, I have 65 shown the form which I, at the present time, consider to be the best embodiment of my invention when applied to shunt contacts for circuit breakers and in which—

Figure 1 is a view of a portion of a circuit breaker having shunt contacts embodying my invention, part of one of the shunt contacts being shown in section; and Fig. 2 is a view of the same circuit breaker in the partly open position in which the main 75 brush is out of engagement with the main contact while the shunt contacts are on the point of separating.

In the particular form of device shown in the drawings, a circuit breaker of any well-known type is mounted upon a suitable panel or support, the circuit breaker being 80 so mounted that the main brush and the shunt contacts swing in a vertical plane and the shunt contacts are above the main contacts. In the particular circuit breaker shown, the main stationary contact 1 is secured to the panel or switchboard and co-operates with the brush 2, while immediately 85 above the main contacts are the secondary metallic contacts 3 and 4 which separate a moment after the main contacts when the circuit breaker opens. The drawings also show the upper end of a pivoted or swinging arm 5 carrying a shunt contact 6 which 90 co-operates with another shunt contact 7 mounted upon the base or panel. By any suitable operating mechanism the arm 5 is actuated and swung about its pivot in such relation to the main brush 2 of the circuit breaker that the circuit remains closed 95 through the shunt contacts after the main contacts have separated so that the arcing due to the final rupture of the circuit takes place between the shunt contacts 6 and 7. 100 In the particular form of contact indicated 105

in the drawings, each shunt contact 6 and 7 consists of a lower part of metal and an upper part or block of carbon which is held in rigid relation to the metallic part of the 5 shunt contacts in any suitable or well known way, but if desired the metal part may be omitted so that the whole engaging face of the contact is carbon.

In order that the shunt contacts 6 and 10 7 may be in good electrical engagement when the circuit breaker is closed they should be held in resilient engagement with each other. It is also very desirable that the shunt contacts be arranged to cause the final break 15 to take place between the carbon surfaces of the shunt contacts so that the unavoidable arcing will cause a minimum amount of damage. In accordance with my invention, the shunt contact 7 is mounted to cause 20 the metallic portions of the shunt contacts to swing away from each other while the carbon portions are still in firm engagement so that the current flowing through the shunt contact is transferred from the metallic 25 portions of the contacts to the carbon portions, and the final break, as well as any arcing caused thereby, takes place between the carbon portions of the shunt contacts. This result is obtained by causing the shunt 30 contact 7 to swing lengthwise of the contact 6 in such a path that points at different ends of the contact 7 traverse different paths which are so related that the lower ends of the contacts are swung away from each 35 other, while the upper ends of the contacts are still in firm engagement. In the particular arrangement shown in the drawing for securing the desired relative movement of the shunt contacts, the contact 7 is carried 40 upon a metallic support 8 mounted at one end upon a pivot 9 secured to the outer ends of two links 10. Since Fig. 1 is a sectional view only, one of the links 10 appears in Fig. 1 while the other is seen in 45 Fig. 2. The links 10 are in turn pivoted at the other ends upon a pivot 11 rigidly mounted in a casing or support 12 secured to the switchboard or panel above the main contacts of the circuit breaker. The upper 50 end of the support 8 and of the contact 7 therefore swing about the pivot 11 as a center and describe a circle having a radius equal to the length of the links 10. The lower end of the contact and of the support 55 8 is guided in any suitable way so that it will follow a path different from the path described by the upper end of the contact 7. In the particular arrangement shown in the drawing the lower end of the contact 60 is guided by links shorter than the links 10 and having a lost motion connection with the contact comprising two lugs 13 secured to opposite sides of the support 8 near its lower end and provided with elongated slots 65 14. Through the slots 14 extends a pin 15

secured to the outer ends of two links 16 considerably shorter than the links 10 and mounted upon a fixed pivot 17 in the framework 12. The short links 16 are preferably mounted to bring their outer ends between the two lugs 13. As a result of the construction above described, movement of the contact 7 relatively to the base or panel causes the two ends of the contact to describe arcs of circles having different radii, 70 and this movement is further modified by the lost motion which takes place between the lower end of the contact and the links 16 on account of the pin 15 and the slots 14. Since the shunt contacts of a circuit breaker 80 are usually mounted to swing in a vertical plane, the weight of the contact 7 will tend to carry it into the position shown in Fig. 1, but in order to make sure that there will be the proper relative movement between the two contacts, I prefer to provide means for resiliently holding the contacts in engagement when the circuit breaker is closed, and in accordance with my invention this result is accomplished with a single spring 85 which may be made strong and rugged and is preferably so mounted that it is covered by the contacts 7 and is protected from accidental injury. In the particular arrangement which I prefer, the support 8 is provided with a lug or projection 18 extending beyond the pivot 9 and connected at its projecting end to one end of a spring 19 which has its other end connected to a pin 20 rigidly mounted in the casing 12. When 100 the circuit breaker is closed the contacts are in engagement and the parts are in the position shown in Fig. 1 with the spring 19 under tension, while as the circuit breaker opens the spring 19 contracts and forces the 105 contact 7 down into the position shown in Fig. 2, with the result that the contact 7 slides longitudinally over the surface of the contact 6 and at the same time its lower end swings away from the lower end of the contact 6 into the position shown in 110 Fig. 2, so that the final rupture of the circuit must take place between the carbon surfaces of the shunt contacts.

In order to insure proper relative movement of the contacts and to bring all parts of the surfaces of the contacts 6 and 7 into firm engagement the slots 14 in the lugs 13 are made long enough to permit the lower end of the contact 7 to swing toward 120 and away from the base and to allow considerable lost motion between the lower end of the contact 7 and the links 16. As a result of this lost motion the contacts are in good electrical engagement with each other 125 during the greater portion of the time that they are in contact and separate in the proper way to throw the arc to the upper edges of the carbons.

The shunt contact 7 may be electrically 130

connected to the circuit in many ways which will be apparent to those skilled in the art, but I prefer to connect it in the manner shown in the drawings by means of a flexible connection 21 fastened at one end to the lower end of the support 8 and to the contact 7 and at the other end to a projection or lug 22 which is connected mechanically and electrically to the main contact 1 so that the circuit is completed from the main contact through the flexible connection 21 to the shunt contact 7. The lug or projection 22 also acts as a stop to limit the downward movement of the contact 7, as shown in Fig. 2.

In a circuit controller having contacts embodying my invention, the contacts are resiliently held in engagement with each other and are compelled to move relatively to each other in such a way that their separation takes place in a predetermined way and at predetermined points. Where the invention is embodied in shunt contacts having both metallic and carbon parts the opening of the circuit breaker separates the contacts in such a way that the metallic portions of the contacts first separate and cause the current to be transferred to the carbon portions where the final break takes place with a minimum of damage. A simple and rugged mounting compels the contacts to move in the desired way, while the resilient engagement of the contacts is effected by means of a single spring so mounted that it is protected from accidental injury or disarrangement.

My invention may be embodied in many other forms than that shown and described and I therefore do not limit myself to the precise arrangement disclosed but intend to cover all changes and modifications within the scope of the appended claims.

What I claim as new and desire to secure by Letters Patent of the United States, is,—

1. In a circuit controlling device, the combination of a contact, means for pivotally connecting said contact to two pivots fixed out of alignment and in the plane of movement of said contact to cause said contact to swing bodily about said pivots, and a co-operating movable contact mounted to move into and out of engagement with said first named contact and thereby swing said first named contact about its pivots.

2. In a circuit controlling device, the combination of a contact, means for mounting said contact to cause two different points thereon to move in circular paths which have different centers and a co-operating contact pivoted to swing about a point eccentric to one of said centers and thereby move into and out of engagement with said first named contact.

3. A circuit controlling device comprising, a contact, a link pivoted to said contact

at one point, means co-operating with said contact at another point to constrain said latter point to follow a path which differs from the arc described by said first point, both of said points moving in circular paths which have different centers, and a co-operating contact pivoted to swing about a point eccentric to one of said centers and thereby move into and out of engagement with said first named contact.

4. A circuit controlling device comprising, a support, a contact mounted on said support, and two links of unequal length each pivoted at one end to different points on said contact and each pivotally mounted at the other end to different points on said support, said links mounted to move said contact toward and away from said support.

5. In a circuit controlling device, the combination of a support, two links of unequal length pivoted to said support at different points, a contact pivotally connected near one end to the longer of said links, and a pivotal lost motion connection between said contact and the shorter of said links at a point near the other end of said contact.

6. In a circuit controlling device, the combination of a support, two links of unequal length pivoted to said support at different points, a contact pivotally connected at the outer end of one of said links, and a lost motion connection between the other said link and said contact for permitting said contact to move to a limited extent toward and away from said support.

7. In a circuit controlling device, the combination with a support, of two links pivoted to said support, a contact pivoted to the outer end of one of said links and having a lug projecting toward said support, resilient means connected to said support and to said lug to move said contact away from said support, and a lost motion connection between said contact and the other link for permitting said contact to move toward and away from said support.

8. A circuit controlling device comprising, a support, links of unequal length pivoted to said support, a contact pivotally secured to the outer ends of the longer links, said contact having at one end a lug which projects toward said support and at the other end lugs with slots therein, a spring one end of which is secured to said lug and the other end to said support, a pin pivotally connected to the outer ends of the shorter links and extending into the slots in the lugs on said contact to form a lost motion connection therewith, and a flexible conducting connection between said contact and one lead of the circuit to be controlled.

9. In a circuit controlling device, the combination with a base, of a contact having each end pivotally linked to said base to be movable relatively thereto, and a spring

1 mounted between said contact and said base and connected to move said contact relatively to said base.

10. In a circuit controlling device, the
5 combination of a base, a contact, and contact
links pivoted to said base at different points
and to different points on said contact, and
a spring mounted between said contact and
said base with one end connected to said base

and the other end connected to said contact 1
to cause said contact to move about the piv-
ots of said links as centers.

In witness whereof, I have hereunto set
my hand this 28th day of October, 1910.

EDWARD M. HEWLETT.
